UNITED STATES PATENT OFFICE.

HENRY E. MOFFAT, OF WOODSTOCK, CANADA.

FEED-WATER HEATER AND PURIFIER.

No. 796,237.

Specification of Letters Patent.

Patented Aug. 1, 1905.

Application filed November 8, 1904. Serial No. 231,245.

To all whom it may concern:

Be it known that I, HENRY ESSON MOFFAT, gentleman, of Woodstock, in the county of Oxford and Province of Ontario, Canada, have invented certain new and useful Improvements in Feed-Water Heaters and Purifiers; and I hereby declare that the following is a full, clear, and exact description of the same.

This invention relates to certain new and useful improvements in that class of feed-water heaters and purifiers shown and described in the drawings and specification of Letters Patent of the United States No. 540,751, granted to me on the 11th day of June, 1895. In that patent the perforated water-supply pipe passes through the top end of the exhaust-pipe, and interposed between it and the outlet is a baffle-plate to prevent the water sprayed by the supply-pipe into the upper end of the feed-water heater and purifier being driven through the outlet by the pressure of the exhaust-steam. This construction, however, has been unsatisfactory, as the metallic and mineral matter in the feed-water precipitates under the influence of the exhaust-steam and incrusts the bore of the exhaust-pipe, so that in the course of time the passage through it becomes choked and causes the steam to apply back pressure upon the engines and direct pressure upon the filter-beds to tear them from their place in the feed-water heater and purifier.

To render it impossible for the feed-water to enter the exhaust-pipe direct from the water-supply pipe is the primary object of this invention, and this object is attained by protecting the top end of the exhaust-pipe with a diaphragm or water-shed and placing the water-supply pipe between the water-shed and the baffle-plate for the outlet, so that the water discharged into the feed-water heater by the water-supply pipe will be prevented by the diaphragm or water-shed from entering the exhaust-pipe and by the baffle-plate from being driven by the pressure of the exhaust-steam through the outlet, the diaphragm or watershed being of sufficient dimensions and inclinations and having perforations beyond the outer surface of the exhaust-pipe to scatter the water evenly to all parts of the topmost filter.

When the water is heavily impregnated with quicksand and other substances which cannot be retained in the filter-bed, but pass to the bottom of the settling-chamber, it is necessary to provide the feed-water heater and purifier with a means by which such sediment can be

expeditiously flushed out of the settling-chamber and settling-chamber filter to prevent it entering the pure-water chamber, and this means consists of a flushing-pipe inserted through the outer casing of the apparatus above the settling-chamber filter-bed, so that a stream of water can be discharged upon it to wash the sediment to the bottom of the settling-chamber, where it can be carried off through an opening in the side of the feed-water heater and purifier at a lower elevation than the bottom of the settling-chamber, the discharge of the impurities through such opening being accelerated by a second flushing-pipe located between the bottom of the filter and the bottom of the settling-chamber. In the bottom of the settling-chamber is a concaved or curved indentation, below its top surface and fitted through the casing of the feed-water heater and purifier is a blow-off pipe, the inner end of which is opposed to such concavity or indentation to allow of the impurities flowing unobstructedly out of the settling-chamber when the flushing-pipes are discharging water thereinto for cleansing purposes. By means of this flushing apparatus the settling-chamber filter and the settling-chamber can be thoroughly cleansed during the operation of the apparatus.

For a full understanding of the invention reference is to be had to the following description and to the accompanying drawings, in which—

Figure 1 is a front elevation of the feed-water heater and purifier, partly in section, to show the relative position of the various parts. Fig. 2 is a sectional view through the settling-chamber and filter, taken at right angles to Fig. 1 to show the position of the flushing-pipes. Fig. 3 is a detail view of the bottom of the settling-chamber.

Like letters of reference refer to like parts throughout the specification and drawings.

As the general construction of the feed-water heater is similar to that shown and described in the above-mentioned patent, it will not be necessary in the present application to describe any of the parts other than those to which the present invention directly relates.

The exhaust-steam enters the feed-water heater from the oil-extractor through the first section *a* of the exhaust-pipe, which has its inlet-port in circulation with the cylinder of the oil-extractor *a'* and its outlet-port *b* discharging into the feed-water heater above the top of the settling-chamber *c*. Covering the

top of the first section *a* is a baffle-plate *d* to distribute the steam across the bottom of the second filter *e*, through the center of which passes the second section *f* of the exhaust-pipe, preferably superimposed on the baffle-plate of the first section *a*. The second section *f* of the exhaust-pipe has an inlet-port *g* below the bottom of the second filter *e* and an outlet-port *h* above the top of the same filter, and covering the top of the second section *f* is a baffle-plate *i* for the same purpose as the baffle-plate *d*. Above the baffle-plate *i* is the third filter *j*, through the center of which extends the third section *k* of the exhaust-pipe, having an inlet-port *l* below the bottom of the third filter and an outlet-port *m* above the top of the same filter. Covering the top of the third section of the exhaust-pipe is a water-shed *o*, projecting considerably beyond the outer surface of the exhaust-pipe, and located above the water-shed *o* is the water-supply pipe *p*, preferably imperforate, to be connected with any suitable source of supply. The discharge end of the water-supply pipe *p* has a downturned elbow *p'* located immediately over the imperforate center of the water-shed *o*, so that the in-rushing water will flow toward the edge of the water-shed and pass over it and through the perforations *o'* to the top of the third filter *j*. To prevent the inflowing water from the water-supply pipe *p* being driven through the outlet *q*, a baffle-plate *r* is interposed between the water-supply pipe and outlet *q*, the baffle-plate being of sufficient dimensions to cover the discharge-openings of the pipe.

The water enters the feed-water heater and purifier through the water-supply pipe *p* and striking upon the water-shed *o* is distributed to all parts of the top surface of the filter *j*, through which and the filter *e* it descends to the inclined plate *s*, which directs it into the settling-chamber *t*, together with any sediment, such as quicksand or other non-detainable impurities, which succeed in passing through the upper filters. From the settling-chamber *t* the water percolates through the settling-chamber filter *u* into the pure-water chamber *v*, from which it is drawn off and returned to the boilers. The pure-water chamber may be provided with an overflow-pipe *w*. To remove the sediment from the settling-chamber and the filter *u*, a flushing-pipe *x* is fitted into the feed-water heater and purifier above the top of the filter *u*, so that it will discharge a stream or streams of water directly upon the top of the filter to wash any sediment which may have accumulated in the filter-bed into the bottom of the settling-chamber *t*, from which it is discharged by the blow-off pipe *z*. The bottom of the settling-chamber *t* is cleansed, and the discharge of the sediment and impurities in the chamber is accelerated by a second flushing-pipe *a'*, located below the bottom of the filter *u*, through which a stream of water is delivered

to the settling-chamber for that purpose. To insure the removal of all the sediment, the bottom *b'* of the settling-chamber has a concavity or recess *c'* below the level of the surface of the bottom, and lining with this recess *c'* is the bore of the blow-off pipes *z*.

Having thus fully described my invention, what I claim as new, and desire to secure by Letters Patent, is—

1. In a feed-water heater and purifier having steam inlet and outlet ports, the combination of a filter interposed between the steam inlet and outlet ports, a steam-pipe extending through the filter and communicating with the steam inlet and outlet ports, a baffle-plate having an imperforate portion covering the outlet end of the steam-pipe and a perforate portion surrounding the imperforate portion, and a feed-water-inlet pipe having a discharge-port opposed to the imperforate portion of the baffle-plate.

2. In a feed-water heater and purifier having steam inlet and outlet ports, the combination of a filter interposed between the steam inlet and outlet ports, a steam-pipe extending through the filter and communicating with the steam inlet and outlet ports, a baffle-plate having an imperforate portion covering the outlet end of the steam-pipe and a perforate portion surrounding the imperforate portion, a feed-water-inlet pipe having a discharge-port opposed to the imperforate portion of the baffle-plate, and a second baffle-plate interposed between the feed-water-inlet pipe and the steam-outlet.

3. In a feed-water heater and purifier, the combination of a filter, a settling-chamber located below the bottom of the filter, a pure-water chamber, a second filter interposed between the settling-chamber and the pure-water chamber and located above the bottom of the settling-chamber, a flushing means above the top of the second filter to wash the sediment from it into the settling-chamber, and a second flushing means below the bottom of the second filter to flush the sediment from the settling-chamber, and an outlet-pipe for the settling-chamber, the bore of which is below the bottom of the settling-chamber, said bottom having a depression in it opposed to the bore of the outlet-pipe.

4. In a feed-water heater and purifier the combination of a settling-chamber having its bottom head disposed in a substantially horizontal plane with a depression therein below its top surface and extending to the edge, a horizontally-disposed outlet-port for the settling-chamber the bottom of which is in the same plane as the bottom of the depression and a flushing means to cleanse the sediment within the settling-chamber and on the bottom head into the depression and through the outlet-port.

5. In a feed-water heater and purifier the combination of a settling-chamber having its

bottom head disposed in a substantially horizontal plane with a depression therein below the level of its top surface extending to its edge, a horizontally-disposed outlet-port opposed to such depression the bottom of which is in the same plane as the bottom of the depression and a flushing means discharging directly upon the filter to wash the sediment through it into the settling-chamber and from the settling-chamber and bottom head to the depression and the outlet-port.

6. In a feed-water heater and purifier the combination of a settling-chamber having its bottom head disposed in a substantially horizontal plane, with a depression therein extending to its edge, and an outlet-port opposed to such depression, a filter suspended above the bottom head of the settling-chamber, a flushing means discharging directly upon the

filter to wash the sediment through it into the settling-chamber and a second flushing means interposed between the filter and the bottom head of the settling-chamber.

7. In a feed-water heater and purifier the combination of a settling-chamber having an outlet-port, a pure-water chamber, a filter interposed between the settling and pure-water chambers, an interiorly-located flushing means discharging directly upon the filter, and a second interiorly-located flushing means below the bottom of the filter and above the bottom head of the settling-chamber.

Toronto, October 17, A. D. 1904.
